[57] CLAIM

The ornamental design for a water bottle, as shown and described.

DESCRIPTION

FIG. 1 is a front and right side perspective view from above of a water bottle showing our new design;

FIG. 2 is a top plan view of the water bottle;

FIG. 3 is a front elevation of the water bottle, the rear elevation is the same except for the conventional, continuous screw threading on the bottle neck;

FIG. 4 is an elevational view showing a portion of the rear and left side of the water bottle;

FIG. 5 is a left side elevation of the water bottle, the right side elevation is the same except for the conventional screw threading on the bottle neck; and,

FIG. 6 is a bottom plan view.
